US00D857661S

(12) **United States Design Patent** (10) **Patent No.:** **US D857,661 S**
Shigeta et al. (45) **Date of Patent:** **** Aug. 27, 2019**

(54) **REMOTE CONTROLLER FOR TOILET SEAT WITH BIDET**

(71) Applicant: **TOTO, Ltd.**, Kitakyushu-shi, Fukuoka (JP)

(72) Inventors: **Ayaka Shigeta**, Kitakyushu (JP); **Minoru Tani**, Kitakyushu (JP)

(73) Assignee: **TOTO, Ltd.**, Kitakyushu-shi, Fukuoka (JP)

(**) Term: **15 Years**

(21) Appl. No.: **29/627,747**

(22) Filed: **Nov. 29, 2017**

(51) **LOC (12) Cl.** **14-03**

(52) **U.S. Cl.** **USPC D14/218**

(58) **Field of Classification Search**

USPC **D14/218; D13/168**
 See application file for complete search history.

(57) **CLAIM**

The ornamental design for a remote controller for toilet seat with bidet, as shown and described.

DESCRIPTION

FIG. 1 is a front perspective view of a remote controller for toilet seat with bidet showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the drawings illustrate portions of the remote controller for toilet seat with bidet that form no part of the claimed design.

1 Claim, 4 Drawing Sheets
